CLAIM

The ornamental design for a cushion trim for an automobile seat, as shown and described.

DESCRIPTION

FIG. 1 is a front perspective view of a cushion trim for automobile seat showing our new design;

FIG. 2 is a front elevational view thereof;

FIG. 3 is a cross-sectional view along the lines 3—3 of FIG. 2 thereof;

FIG. 4 is an alternate cross-sectional view taken along the line 4—4 of FIG. 2 thereof; and,

FIG. 5 is a rear elevational view thereof.

The automobile seat depicted by means of broken lines in FIG. 1 has been shown for environmental purposes only and forms no part of the claimed design.

FIG. 2

FIG. 3

FIG. 1

FIG. 4

FIG. 5
